H. R. IRWIN,
WATER MOTOR.

APPLICATION FILED MAR. 18, 1912.

1,036,630.

Patented Aug. 27, 1912.

UNITED STATES PATENT OFFICE.

HARRY R. IRWIN, OF FORT THOMAS, KENTUCKY.

WATER-MOTOR.

1,036,630.

Specification of Letters Patent. Patented Aug. 27, 1912.

Application filed March 18, 1912. Serial No. 624,434.

To all whom it may concern:

Be it known that I, HARRY R. IRWIN, a citizen of the United States; and a resident of Fort Thomas, in the county of Campbell and State of Kentucky, have invented certain new and useful Improvements in Water-Motors, of which the following is a full, clear, and exact description, reference being had to the accompanying drawing, forming part of this specification.

My invention relates to water or fluid pressure motors of the reciprocating type for driving light machinery, and the object of the invention is to provide a construction in which a spring of comparatively large size may be employed for assisting the reversal of the valves at the conclusion of each stroke to reverse the action of the motor. At the same time, the construction is designed to economize the space for the spring and to enable me to provide a compound valve of comparatively large size, whereby the efficiency of the motor may be largely increased, and the operation may be insured for a large range of water pressures.

Other features of novelty and advantage will be pointed out in the progress of the description and referred to in the claims.

In the drawing, Figure 1 is a central longitudinal section of my improved motor. Fig. 2 is a side elevation of the compound inlet and exhaust valve structure. Fig. 3 is an end elevation of the compound valve.

The motor cylinder 1 is formed of any convenient size, with a head 2 at one end and a valve casing 3 at the opposite end. The piston 4 is adapted to reciprocate in the motor cylinder under the fluid or water pressure, and it is provided with a piston rod 5, which is formed with a rack, or otherwise arranged to be suitably connected with the machine to be driven by the motor. This piston rod is provided with the usual stuff-

ing box 6, to prevent leakage as the piston is reciprocated. Mounted in the valve casting 3 at the opposite end of the cylinder and in axial alinement with the piston and piston rod is the compound inlet and exhaust valve.

This valve structure comprises a double puppet exhaust valve formed of disks 7, 8, connected by wings 9, 10, leaving the space between the disks hollow or open; and the outer edges of the wings forming a guide for the sleeve 12, which forms the double puppet inlet valve. This sleeve is provided

with a series of apertures 13 to allow passage of the fluid from the space between the wings on the exhaust valve into the annular passageway 14 formed in the interior 60 cylindrical casing 15, which surrounds the sleeve 12 and in which the sleeve valve slides. The annular passageway 14 is provided with a port 16 into the exhaust pipe 17.

Each end of the sleeve valve 12 is provided with a double valve seat 18, 19, at one end, and 20, 21, at the other. The valve seats 18 and 20 have their bearings respectively on corresponding seats 22, 23, formed in the respective ends of the casing, the seat 22 being formed on the inner edge of the cap 24, which is screw-threaded into the casing and forms a part thereof, the cap being provided to permit the compound valve to be located in place. The inner seats 19 and 21 of the sleeve valve 12 have their bearing on the corresponding seats 25, 26, of the disks 7 and 8 of the double puppet valve.

The valve disk 8 is provided with a short stem 27, upon which is screwed the hollow cap 28, provided with a central aperture through which passes a rod 29 with the head 30 of this rod secured in the hollow cap. Upon the other end of the rod 29 and inside 85 the two walls 31, 32, of the piston are loosely mounted the two disks 33, 34. The disk 33 is provided with a sleeve 35, projecting inwardly and loosely around the rod 29. The head 36 of the rod 29 engages the outer 90 side of the disk 34, the rod passing through the two disks. A coiled spring 37 of comparatively large size is mounted between the two disks 33, 34, normally holding them in engagement with the inner surfaces of the 95 walls of the piston, while the piston is provided with the chamber 38 to receive this spring. The piston rod 5 is cored to form a space 39 so as to allow the rod 29 to extend into the piston rod when the piston is reversed.

The water or fluid under pressure is supplied to the motor through the inlet pipe 40, and in the position shown in the drawings the water under pressure is entering 105 the cylinder through the passageway 41, and has driven the piston to the right. The exhaust water from the opposite side of the piston passes out through the port 42, passageway 43, along the cylinder into the 110 chamber 44 in the valve chest, and in the position of the valves shown in the draw-

ings, the exhaust is passing around the valve seat 25 into the sleeve valve 12, and out through the openings 13 and the annular passageway 14 through the port 16 into the exhaust pipe 17. In this position of the piston, the head 36 has just come in contact with the disk 34, and as the water pressure on the inlet side of the piston is holding the valve disk 8 to its seat, the spring with further movement of the piston to the right is compressed, and under ordinary high water pressures the spring 37 compresses until the hub of the disk 34 comes in contact with the hub of the disk 33, in which position the puppet valve 7, 8, is shifted by the rod 29, the first movement causing the valve disk to seat itself on the seat 19 of the sleeve valve, thus cutting off the exhaust, and at the same time shifting the valve disk 8 from its seat 21, allowing the water under pressure to escape into the sleeve valve 12 and thence to the exhaust. The water under pressure in the cylinder, with the shifting of valve disk 8 from its seat 21 is then relieved, as this water has an outlet into the sleeve 12 and out through the exhaust and the spring 37 instantly shifts the disk 34 back to its normal position and draws the sleeve valve to the right, thus closing the inlet 41, and the passage between the valve seat 21 and 26 becomes the exhaust passageway for the former pressure side of the cylinder, while the inlet water passes into the valve chamber 44 and thence through the passageway 43 and port 42 into the former exhaust side of the cylinder, reversing the movement of the piston. When the piston has moved to the left until the sleeve 35 on the disk 33 contacts with the head of the cap 28, the spring 37 is again compressed until the hubs of the disks 33 and 34 are brought in contact, when the puppet valve is again shifted to close the exhaust port and the spring 37 returns the disk 33 to its normal position, returning the puppet and sleeve valves to their first position as shown in the drawings, and the piston is again reversed in its movement.

The construction illustrated operates with efficiency with either low or high water pressures. When the pressure is quite low, the disks 33 and 34 may not be brought together, and the shifting of the valves will take place as soon as the tension of the spring overcomes the live pressure on the puppet valve.

Not only do I have the assistance of the spring 37 to complete the movement of the inlet valve, but the initial movement of the puppet valve coming in contact with the sleeve valve tends to shift it and allow the live pressure to itself throw the valve to its opposite seat.

In the construction illustrated, it will be noted that the exhaust valve is first shifted,

and in this I believe my construction differs from all other types of water motors in that, in the older constructions either the inlet valve is given the initial movement or both valves are shifted simultaneously. In my construction, I completely reverse the exhaust before the inlet valve is shifted.

While compound valve structures are not new, I believe it has been customary to form the seat for such valves by a peripheral flange between the parts of the valve. In my construction, however, it will be noted that all of the valves are provided with ground seats and thus there is no danger of leakage, as there is where a peripheral seat is provided. By seating the assisting spring 34 within the hollow piston, I economize space in the length of the motor, and by reason of the construction I am able to provide a comparatively large spring which is very slightly subject to crystallization, a danger frequently experienced with coiled springs of small diameter.

While I have illustrated my construction with reference to the cylindrical type of reciprocating motor, it will be obvious that the construction of valve is equally applicable to the rotary type of such motors, and in the use of the term "reciprocating type," I wish it to be understood as applying to both forms of motor.

Having thus described my invention, what I claim as new and desire to secure by Letters Patent, is:—

1. In a machine of the character specified, a motor casing and a piston adapted to reciprocate therein, forming alternately pressure and exhaust chambers in said casing, a valve chamber with passageways on each side of said piston from the piston chamber to the valve chamber alternately serving as inlet and exhaust ports, an inlet and an exhaust pipe for said valve chamber, and a double compound valve in said valve chamber comprising an exhaust valve mounted inside of the inlet valve, said inlet valve having seats for the exhaust valve, and mechanism intermediate said compound valve and the piston whereby said valve may be actuated at the completion of the piston stroke in either direction to shift the valve to reverse the water pressure from one side of the piston to the other.

2. In a machine of the character specified, a motor casing and a piston adapted to reciprocate therein, forming alternately pressure and exhaust chambers in said casing, a valve chamber with passageways on each side of said piston from the piston chamber to the valve chamber alternately serving as inlet and exhaust ports, an inlet and an exhaust pipe for said valve chamber, and a double compound valve in said valve chamber, comprising a double puppet exhaust valve with a double puppet inlet valve

mounted to slide thereon, with the exhaust valve seats upon the inlet valve, and mechanism intermediate said compound valve and the piston whereby said valve may be actuated at the completion of the piston stroke in either direction to shift the valve to reverse the water pressure from one side of the piston to the other.

3. In a machine of the character specified, 10 a motor casing and a piston adapted to reciprocate therein, forming alternately pressure and exhaust chambers to said casing, a valve chamber with passageways on each side of said piston from the piston chamber 15 to the valve chamber alternately serving as inlet and exhaust ports, an inlet and an exhaust pipe for said valve chamber, and a double compound valve in said valve chamber, a double acting spring mounted in said 20 piston, and plates normally separated by said spring, one of said plates adapted to be engaged by said compound valve at one end of the piston stroke, and a connecting rod to connect said valve and the other plate 25 at the other end of the piston stroke to shift the valves to reverse the piston movement.

4. In a device of the character specified, embodying a motor chamber with a reciprocating piston, a double acting compound 30 valve comprising a double puppet exhaust valve and a double puppet inlet valve mounted thereon to slide axially, the double puppet exhaust valve having positive seats upon the inlet valve whereby the shifting 35 of the exhaust valve will assist in unseating the inlet valve.

5. In a device of the character specified, embodying a motor chamber with a reciprocating piston, a double acting compound 40 valve comprising a double puppet exhaust valve and a double puppet inlet valve mounted thereon to slide axially, the double puppet exhaust valve having positive seats upon the inlet valve whereby the shifting of 45 the exhaust valve will assist in unseating

the inlet valve, and a spring interposed between the exhaust valve and the piston to assist in shifting the inlet valve upon the completion of the piston stroke in either direction.

50

6. In a device of the character specified, embodying a motor chamber with a reciprocating piston, a double acting compound valve comprising a double puppet exhaust valve and a double puppet inlet valve 55 mounted thereon to slide axially, the double puppet exhaust valve having positive seats upon the inlet valve whereby the shifting of the exhaust valve will assist in unseating the inlet valve, a double acting spring 60 mounted in said piston, and plates normally separated by said spring, one of said plates adapted to be engaged by said compound valve at one end of the piston stroke, and a connecting rod to connect said valve and 65 the other plate at the other end of the piston stroke to shift the valves to reverse the piston movement.

7. In a machine of the character specified, 70 a motor casing and a piston adapted to reciprocate therein, forming alternately pressure and exhaust chambers to said casing, a valve chamber with passageways on each side of said piston from the piston chamber to the valve chamber alternately serving 75 as inlet and exhaust ports, a double compound valve and an inlet and an exhaust pipe for said valve chamber, a double acting spring mounted in said piston, and plates normally separated by said spring, one of 80 said plates adapted to be engaged by said compound valve at one end of the piston stroke, and a connecting rod to connect said valve, and the other plate at the other end of the piston stroke to shift the valves to 85 reverse the piston movement.

HARRY R. IRWIN.
